(57) **CLAIM**

The ornamental design for an adjustable tie down device, as shown and described.

DESCRIPTION

FIG. 1 is a perspective view of an adjustable tie down device, showing our new design;

FIG. 2 is a top plan view thereof;

FIG. 3 is a front view thereof;

FIG. 4 is a left side view thereof;

FIG. 5 is a right side view thereof;

FIG. 6 is a rear view thereof; and,

FIG. 7 is a bottom view thereof.

The broken line showing of a hook is included for the purpose of illustrating a portion of an adjustable tie down device and forms no part of the claimed design.
